D. J. MACHOL

DENTAL SYRINGE

Filed Oct. 15, 1921

Inventor
David J. Machol.
By his Attorney
Edward A. Jarvis

UNITED STATES PATENT OFFICE.

DAVID J. MACHOL, OF WEST NEW BRIGHTON, NEW YORK.

DENTAL SYRINGE.

Application filed October 15, 1921. Serial No. 507,881.

To all whom it may concern:

Be it known that I, DAVID J. MACHOL, a citizen of the United States, residing at West New Brighton, county of Richmond, State of New York, have invented certain new and useful Improvements in Dental Syringes, of which the following is a full, clear, and exact description.

This invention relates to improvements in dental syringes, one of the objects being to provide a syringe arranged for the purposes of cleansing cavities in the teeth or for whatever use in connection with the treatment of the teeth that may be necessary or desirable. During the operation of treating the teeth, more especially filling the cavities are cleansed with warm water, and are also subjected to treatment by warm air. My improved syringe is designed for attachment to a water supply, a water faucet, or dental fountain and includes a heater through which the water passes on its way to the syringe nozzle, the heater containing a heating element, such as an electrical resistance, which acts to heat the water. The casing containing the heat is also arranged for the introduction thereto of air under pressure, special means being provided to connect the air chamber with the nozzle member of the syringe for the purpose of introducing warm air into a cavity of a tooth, if desirable. In other words, my improved syringe is arranged to introduce either warm water or warm air into the cavity of a tooth, the same nozzle being used for both purposes. The foregoing is a general description of my invention, a more detailed account will follow.

In the drawing which forms part of this specification,

Fig. 1 is a sectional view, partly in elevation of my improved syringe;

Fig. 2 is an end view thereof, looking from the left in Fig. 1, certain parts being omitted;

Fig. 3 is an enlarged sectional view illustrating the associated air and water ducts and valves; and

Fig. 4 is a sectional view of the nozzle member, the section being taken on a line 4-4 in Fig. 1.

As herein embodied, my invention is made up of a heater 5, a nozzle member 6 and a duct or flexible tube 7, which connects the nozzle and heater. Further elements of the device are a duct or flexible tube 8 to con-

nect the heater with a source of water supply, and a duct or flexible tube 9 connecting the heater and source of compressed air supply. The water and air supply have not been illustrated, but the tube 8 may be connected to a water faucet, a dental fountain, or any other source. The tube 9 may be connected to a tank, containing compressed air or a foot pump. The heater consists of a casing 10 having a bracket 11 by which means, and screws 12, the heater can be permanently fastened to any element adjacent the dental chair, such for instance as the side of a cabinet wall, etc. The bracket 12, in this instance, includes an extension 13 which carries a switch mechanism 14, which controls the circuit for the resistance coil or heating unit 15 within the casing 10. In this instance the unit 15 is tubular, the water passing through the bore 16. The unit 15 is supported by cones 17, 17', preferably made of relatively soft rubber, the cones 17, 17', being carried by nipples 18, 18' which also carry a nut 19 threaded at 20. Each nut 19 is screwed into an opening in its adjacent head 21, the head being fitted in the ends of the casing 10. By this means I avoid the use of bolts or screws to hold the unit in place thereby eliminating, to a large extent, breakage, as the unit can be positioned within the casing, or removed therefrom by the proper manipulation of the nuts 19. The nipple 18, at one end of the casing, has attached thereto the water duct 8, while the nipple 18' at the opposite end of the casing has connected therewith the duct 7 which connects the heater and nozzle 6. Strictly speaking, the nozzle 18' at its outer end is connected to a T 22 to which the duct 7 is connected, as indicated in Fig. 3. The T 22 also carries a nipple or by-pass 23 connected, at its upper end to a casing 24 containing a valve 25, which closes or opens a port 26 in said casing. The port 26 communicates with a nipple 27 placed in communication with the air chamber 28 surrounding the heating unit 15. The T 22 is provided with a check valve 29 which closes the opening through duct 18' when air is used. The circuit for the heating unit is controlled by the switch mechanism 14 consisting of a switch arm 29 pivoted at 30 to the extension 13. In connection with arm 29 I employ a contact 31 carried by a block of insulating material 32. The contact 32 is

connected to one end of coil 33 by a lead 34, in this case the negative side of the line, while the arm 29 has connected thereto the cooperating circuit wire 35. When nose-piece 36 on arm 29 contacts with contact 31, the circuit for the coil will be closed. The arm 29 will be held in raised or circuit closing position, by a light spring 36. The spring 36 at one end is connected to arm 29, and at the other end to a lever 37 pivoted at 38 to a bracket 39 carried by extension 13. When arm 37 is located to the left of a vertical position, relative to its pivot point, spring 36 will act to raise arm 29. When lever 37 is positioned to the right of a vertical position, relative to the pivot point 38, spring 36 will not act and the arm 29 will remain in its lowermost or circuit breaking position. The nozzle member consists of a casing 39 containing a valve 40 operable by hand by means of a lever 41. The valve acts to control the flow of water or air through the duct 42 in casing 39. The nozzle casing 39 carries a hook 43 to engage switch arm 29, in order that said nozzle can be hung upon the switch arm when the device is not in use thereby maintaining the circuit for the coil 33 open. When the device is to be used, the nozzle 6 will be removed from the switch arm after which spring 36 will move arm 29 to close the circuit for the coil. After the circuit has been closed, the water within the unit 15 will become heated, after which valve 40 will be opened by the thumb, for instance, on the hand of the operator holding the nozzle whereby warm water will flow from the nozzle spout 44. The tube 7 will be relatively small as compared to the capacity of the bore 16 of the unit 15; hence, the inflowing water will pass slowly through the unit and have time to become heated. Should the operator desire warm air instead of water, the water supply will be turned off and valve 25 opened. When valve 25 is opened, the pressure of air will close the check valve 29 thereby will prevent air from flowing back through the water supply ducts. Before using the nozzle for air, the operator will, of course, allow all of the water to be forced out of duct 7 and nozzle before applying the nozzle for use, that is in the event of the alternate use of water and air. The chamber 28 may at all times contain air under pressure or may have air

under pressure admitted thereto just prior 55 to the use of the syringe for the application of air. Current for the coil may be obtained by plugging into a light circuit or from any suitable source of electrical supply. Should it be desirable to operate the cold water, arm 60 37 will be moved to the right thereby removing all the tension from spring 36 after which arm 29 will stay down and the circuit for the coil will remain open.

What I claim and desire to secure by Letters Patent is:—

1. In a dental syringe, a casing closed at both ends, a tubular electrical heating element within the casing, said element being smaller in diameter than said casing to provide an air chamber around said heating element, means to pass water through said tubular heating element, means to introduce air into the chamber around the heating elements, a nozzle, a flexible duct connecting 70 the tubular heating element and said nozzle, means to connect the air chamber with said duct at will, and a check valve to prevent air from flowing into the heating unit. 75

2. In a dental syringe, a casing closed at both ends, a tubular electrical heating element within the casing, said element being smaller in diameter than said casing to provide an air chamber around said heating element, means to pass water through said tubular heating element, means to introduce air into the chamber around the heating elements, a nozzle, a flexible duct connecting the tubular heating element and said nozzle, a supplemental duct connecting the air chamber with said flexible duct, and a valve 80 to control the flow of air into the flexible duct carried by the supplemental duct. 85

3. In a dental syringe, a nozzle member, an electrical heating coil, a circuit therefor, a switch included in the circuit, means carried by the nozzle to engage said switch to maintain said circuit open when the switch is not in use, and manually operable means 90 to operate the switch to maintain said circuit open independently of said nozzle. 100

Signed at New York city, N. Y., this 29th day of September, 1921.
